CLAIM

The ornamental design for laser distance measuring apparatus as shown and described.

DESCRIPTION

2. Laser distance measuring apparatus

2.1: Front, Right, Top Perspective

2.2: Front

2.3: Rear

2.4: Left

2.5: Right

2.6: Top

2.7: Bottom

The broken lines depicting a boundary around the de-emphasized elements, and the de-emphasized elements

(Continued)

within, illustrate portions of the laser distance measuring apparatus which form no part of the claimed design.
